UNITED STATES PATENT OFFICE.

ISAAC REESE, OF MEMPHIS, TENNESSEE.

AIR AND WATER MOTOR.

1,148,989.

Specification of Letters Patent. Patented Aug. 3, 1915.

Application filed September 12, 1914. Serial No. 861,422.

To all whom it may concern:

Be it known that I, ISAAC REESE, a citizen of the United States, and a resident of Memphis, in the county of Shelby and State 5 of Tennessee, have invented an Improvement in Air and Water Motors, of which the following is a specification.

My present invention relates generally to power generating motors and more particularly to a combined air and water motor of such a nature as that the submerged and exposed portions respectively subject to water and air currents may each be operated to the exclusion of the other or one may be operated with the assistance of the other, and in which the partially or wholly inactive portion cannot be acted upon to the detriment of the partially or wholly active portion. These and other objects and the advantages arising therefrom I accomplish by an arrangement which may be generally stated to include a partially submerged shaft having a series of power generating wheels loosely associated both upon its submerged and exposed portions, through ratchet and pawl connections, the particular construction of the wheels and their connections being such that they can only be driven in one direction, respective to the direction of the water and air currents, and the stated connections with the shaft being such that the exposed wheels may be disengaged and thus avoid dragging through the air when the submerged wheels are driven at a speed greater than the velocity of the air currents, and vice versa.

These objects and advantages briefly stated above will be better understood from the following description in which reference 40 is made to the accompanying drawings, forming part of this specification, and in which—

Figure 1 is a view, partially diagrammatic, illustrating an arrangement constituting my invention in side elevation, certain of the parts of which are broken away and in section. Fig. 2 is a plan view of one of the power generating wheels with its feathering blades. Fig. 3 is a section taken diametrically through the wheel shown in Fig. 2 and substantially on line 3—3 of said figure. Fig. 4 is a view similar to Fig. 2

illustrating a slightly modified form of power generating means, and Fig. 5 is a sectional view taken diametrically through the 55 figure shown in Fig. 4 and substantially on line 5—5 of said figure.

Referring now to Fig. 1 I have shown a shaft generally indicated at 9, in upright position and with its lower half submerged 60 below the water line of a stream, and which shaft may be either in a single piece or in a plurality of sections, in either case being mounted in roller bearings generally indicated at 16 and supported within a crib or 65 like structure indicated at A. This crib, which may be provided with guard bars A', connected by cross rods for preventing the entrance of drift wood or other debris, may be erected in a variety of forms, its particular form being unessential so long as provision is made for the support of the bearings 16 and the upper bearings 21 of a counter shaft 20 connected by gears 18 and 19 to the upper end of the shaft 9 before 70 mentioned and on which is mounted a pulley 22 from which the power generated by the means to be hereinafter described may be effectively transferred to the point of storage or utilization. Upon the shaft 9, or 75 upon the several portions thereof, if it is to be in sections, are loosely disposed a plurality of power generating wheels B and B', the former having blades upon one side only and the latter having blades upon both sides. 80 As shown, the generating wheels B and B' are distributed equally upon the exposed and submerged portions of the shaft 9 respectively subject to the action of air and water currents, but this is not essential and 85 cannot of course be maintained as the power generator as a whole is ordinarily erected in tidal waters and running streams. In any case, the several power generating wheels B and B' are connected to the shaft 9, or the 90 sections thereof, by means of pawl and ratchet connections, the ratchets being connected at 14 and the pawls at 15 in Fig. 1.

The several power generating wheels B and B' can by their particular construction, 100 be driven in one direction only, that is clockwise, in Fig. 1 and, considering the particular connections with the shaft 9 as above stated, it will thus be seen that the exposed

portion of the motor, subject to the action of air currents is an assistance up to the full velocity of the water currents acting upon the submerged portion, and vice versa, and that whenever the velocity of the wind drives the wheel at a greater speed than that actuated by the flow of the water currents, the pawls 15 of the submerged wheels will slide over their ratchets 14 and thus permit the greater speed of the shaft 9 without the disadvantage of dragging the blades of the submerged wheels through the water. This is equally true, of course, of the exposed portion of the motor as a whole when the speed imparted to the shaft 9 by the action of the water currents against the submerged wheels exceeds that imparted by the air currents to the exposed wheels.

Each of the wheels B and B' indicated in somewhat diagrammatic form in Fig. 1 is, in its details, like the wheels shown in Figs. 2 and 3, consisting of an outer rim 1, spokes 2, a series of bearings 3 around the rim adjacent the outer ends of the spokes, a hub 4, and a plurality of shafts 5 which extend diametrically through the hub 4 and have their outer ends journaled in the bearings 3 at diametrically opposite points of the rim 1, each of the said shafts thus having portions upon opposite sides of the axis of the wheel.

The several feathering blades 7 have stiffening straps 6 by which they are rigidly attached to portions of the several shafts 5, each shaft having its blade 7 upon one side of the axis of the wheel secured thereto parallel to the median plane of the wheel and its other blade 7 upon the opposite side of the axis of the wheel secured thereto in a plane at right angles to the median plane of the wheel. Thus each of the power generating wheels is provided with a series of right angle balancing blades adapted to receive the air or water currents by the blades in operative positions at one side of the wheel while the blades at the opposite side of the wheel are in feathered position, thus eliminating all friction and resistance while in rotation. The same result may be obtained by the arrangement shown in Figs. 4 and 5 in which the shafts 5^a of the wheel are in separate parts upon opposite sides of the wheel axis, and the blades 7^a similarly connected to the shafts 5^a by means of straps 6^a are interconnected in diametrically opposed pairs by means of flexible connections 11 extending over pulleys 10 inside of the wheel and attached to the inner sides of spaced series of spokes 2^a extending between the hub portion 4^a and the rim 1^a, the former of which is connected to the shaft 9^a.

My invention as thus described is especially adapted for use in the streams of regions where there is occasional rise and fall of water, which affords different amounts of energy to the wheels, as the motor as a unit

may be used with equal effectiveness when exposed or submerged more or less in the air or water.

Thus from the foregoing it will be understood that as the submerged and exposed ends of the motor are of the same material and construction, it will operate equally as well more or less submerged than as shown and previously described and will in addition operate as effectively either entirely exposed to air currents or entirely submerged within water currents, with the shaft of the several generating wheels either in vertical or horizontal positions.

I claim:—

1. In a device of the character described, a power generating wheel having spaced apart sides forming an annular chamber therebetween, pulleys mounted on said sides and arranged within the said annular chamber, each of said sides of the wheel having a hub portion and a rim portion, a plurality of shafts journaled at each side between its hub and rim and defining therewith substantially rectangular spaces, a plurality of substantially triangular severing blades adapted to fit within said spaces and carried by said shafts, said blades being arranged in pairs at each side of the wheel, the blades of each pair of which are disposed upon diametrically opposite sides of the respective hub portion, and flexible connections between the blades of the spaced sides whereby to cause simultaneous movement of the blades of each pair, one to operative position and the other to feathered position, said flexible connections extending within the said annular chamber and around the said pulleys therein.

2. In a device of the character described, a power generating wheel having spaced apart sides, each of which sides has a hub portion and a rim portion, a plurality of shafts journaled at each side between its hub and rim and defining therewith substantially rectangular spaces, a plurality of substantially triangular feathering blades adapted to fit within said spaces and carried by said shafts, said blades being arranged in pairs at each side of the wheel, the blades of each pair of which are disposed upon diametrically opposite sides of the respective hub portion, and flexible connections between the blades of the spaced sides whereby to cause simultaneous movement of the blades of each pair, one to operative position and the other to feathered position, said flexible connections extending between the spaced sides of the wheel.

3. In a device of the character described, a power generating wheel having a hub portion and a rim portion, a plurality of shafts extending between the hub and rim and defining therewith a plurality of substantially rectangular spaces, a plurality of substan-

tially triangular feathering blades adapted to fit within said spaces and carried by said shafts, said blades being arranged in pairs, the blades of each pair of which are disposed on diametrically opposite sides of the wheel hub and at right angles to one another, and connections between the blades of

each pair whereby to cause their simultaneous movement, one to operative position and the other to feathered position.

ISAAC REESE.
